UNITED STATES PATENT OFFICE.

JAMES E. CLARK AND THOMAS E. CLARK, OF DETROIT, MICHIGAN.

HUMIDIFIER.

Application filed November 16, 1925. Serial No. 69,551.

This invention relates to means for charging a current of air with medicinal or other vapors and heating such currents if desired, and it consists in a rotatable fan with a 5 supporting housing which is substantially bell-shaped and provided with openings in its flaring portion, and a fabric mounted over the openings and saturated with the liquid to be evaporated. It further consists 10 in attaching an electric heater below the fan so that the humid air may be heated. It also consists in the details of construction illustrated in the accompanying drawing and particularly pointed out in the claims.

15 In the drawing, Fig. 1 is an elevation of a device embodying this novel combined humidifier and heater. Fig. 2 is a bottom plan of a heater. Fig. 3 is an elevation of one of the wire-supporting arms of the heater on a 20 larger scale. Fig. 4 is a section on the line 4-4 of Fig. 3. Fig. 5 is a section of the trough for holding the liquid to be evaporated.

Similar reference characters refer to like 25 parts throughout the several views.

The construction of the electric motor connections, of the bell-shaped housing and of the means for supporting the lamp socket from the housing form no part of the present 30 invention, as they are described and shown in the Thomas E. Clark application, Serial Number 330,282, filed October 13, 1919, and any other suitable motor installation may be employed. The present drawing, therefore, 35 shows merely the bell-shaped housing 1 having the apertures 2 and the rounded lower edge 3; a frame 4 of wires extending down from the edge 3 of the housing and supporting the ordinary lamp socket 5; and the fan 6 mounted on the lower end of a vertical shaft 11 of an electric motor which is not shown in the present drawing.

A jacket 7 of open knitted, netted or woven fabric is placed over the apertures 2 in the 45 flaring portion of the housing 1 and may be held in position thereon by the ring 8. A circular trough 9 may be mounted on the edge of the housing, as shown in Fig. 5, and provided with fingers 10 which extend into 50 apertures 2 and support the wicking 12 which contacts with the lower edge of the jacket 7. The liquid to be evaporated may be poured directly onto the jacket 7 or into the trough 9 from which it will pass to all 55 parts of the jacket through capillary action.

When the fan 6 causes a movement of air through the jacket, the liquid held thereby will be evaporated to humidify the air thus moving through. This liquid may be a perfume, a disinfectant or purely medicinal 60 such as one which is effective for the treatment of scalp troubles, in which case the patient may be seated directly below the fan and his or her hair manipulated to permit the humid air reaching every part thereof. 65 In order to heat this current of air, the following mechanism may be employed. The wire frame 4 supports the ordinary lamp socket 5 into which a plug 15 may be screwed. Strips 16 of mica having holes 17 and reinforced with metal strips 18 of metal are mounted on the plug 15 preferably by securing the ends of the strips 18 thereto. A spiral 19 of high resistance wire is mounted in the holes 17 of the mica and a screen 20 of any 70 desired character may be mounted below the heater.

The device is peculiarly effective for changing and charging the air of large assembly rooms, theaters and the like where 75 large numbers of persons congregate. The air is caused to circulate rapidly and each portion that passes through the jacket leaves behind the dust which it carries so that the air soon becomes free from physical impurities. 80

Any other type of small electric heater may be mounted below the fan 6 and the screen 20 may be omitted, if desired. Pressing the button 22 causes the fan to rotate and a 85 stream of properly charged air to be forced down from the housing. By pulling the cord 23 current is caused to flow through the heating spiral 19, over which the current of air passes from the fan and is warmed thereby. 90 It is evident that the heater may be omitted or removed when desired.

The details and proportions of the various parts may all be changed by those skilled in the art without departing from the spirit of 100 our invention as set forth in the following claims.

We claim:

1. In combination, a substantially bell-shaped housing having apertures in its flaring portion, and a trough secured to the edge of the flaring portion, a jacket of fabric mounted over the apertures in said flaring portion and having its edge extending into said trough, means in the trough to receive 105

liquid and supply it to the fabric, a fan rotatably mounted adjacent the open flaring end and adapted to draw air through the jacket, and an electric heater mounted adjacent the fan to heat the humid air as it comes from the fan.

2. In combination, a symmetrical bell-shaped housing having apertures in its flaring portion and liquid receiving means at 10 its rim, a jacket of fabric mounted over said

apertures and extending to said liquid receiving means to receive liquid therefrom, a rotatable shaft positioned axially of said housing, a fan attached to said shaft at the open end of said housing and adapted to 15 draw air through said apertures and fabric, and an electric heater mounted in the path of the air moved by the fan.
